LINE HOLDER

Kenneth E. Schneider and Gerald W. Schneider,
Borger, Tex.

Application May 26, 1952, Serial No. 289,988

4 Claims. (Cl. 33—85)

1

This invention relates to a line holder and more particularly to a holder for a cord or line such as is employed by masons and others engaged in construction where the work must be arranged in a straight line.

In the construction of buildings and the like it is the present practice of a mason to first construct at opposite ends of a foundation or other wall a corner lead comprising several courses of brick or like building units, and then to stretch a cord between said corner leads to act as a guide with which the intervening bricks or building units are aligned as they are laid. Such methods of construction require that the corner leads be carefully built so that they are plumb and level as well as in proper alignment as otherwise the completed wall will prove faulty.

The primary object of this invention is to support a line or cord in proper position with relation to a wall to be constructed so that the bricks or building units may be laid in proper alignment throughout the entire length of the wall including the corners thereof.

Another object is to support a line or cord at the proper level in surrounding relation to the structure being built.

A further object is to so support the line or cord that it defines the perimeter of the structure under construction.

Still another object is to hold a line or cord in such a position along all walls of the structure that it will define the inner faces of the walls.

The above and other objects may be attained by employing this invention which embodies among its features a vertical standard positioned adjacent each corner of a building structure, a carriage mounted on each standard for vertical movement thereon, means carried by each carriage for engaging its respective standard and holding said carriage in a selected position thereon, arms carried by the carriages and projecting toward the building structure, means carried by the arms for holding a guide line or cord in building structure perimeter defining position, and stops carried by the arms for engaging adjacent walls of the building structure and accurately positioning the guide line in place.

Other features include a guide line supporting yoke carried by the arms remote from the sleeve and extending inwardly between said arms and said yoke having slots therein for receiving and supporting a guide line or cord.

Still other features include an elongated circular cylindrical standard having a longitudinal anchoring fin extending radially therefrom and a

2

longitudinally extending groove opening through the outer side of said standard diametrically opposite the fin, a sleeve mounted on the standard for movement vertically thereon, and a pointed thumb screw extending through and threadedly engaging the sleeve for entering the groove and engaging the standard thereby holding the sleeve against rotation and in a selected vertical position on the standard.

10 In the drawings,

Figure 1 is a fragmentary plan view of a partially constructed building showing one form of line holder of this invention in use.

Figure 2 is an enlarged horizontal sectional view of the line holder illustrated in Figure 1,

Figure 3 is a fragmentary side view of Figure 2,

Figure 4 is a view similar to Figure 1 showing a modified form of line holder,

Figure 5 is a view similar to Figure 2 showing the modified form of the invention, and

Figure 6 is a sectional view taken substantially on the line 6—6 of Figure 5.

Referring to the drawings in detail a building structure designated generally 10 includes a foundation wall 12 adjacent the corners of which are supported vertically disposed standards 14 which as illustrated in Figures 1 through 3 may be angle irons so disposed that the junctions of their flanges are disposed adjacent the corner of the foundation wall. The important condition to be met being that the standards extend vertically true and plumb.

Mounted for vertical sliding movement on each standard 14 is a carriage designated generally 16 which comprises a pair of convergent side members 18 which lie adjacent and parallel with the flanges of the standard 14. A web 20 is carried by and extends between the divergent ends of the side members 18 and carried by the web 20 midway between opposite ends thereof is a boss 22 having an internally screw threaded opening 24 extending therethrough which aligns axially with the junction of the side members 18. A thumb screw 26 extends through and threadedly engages the threads of the opening 24 for clamping engagement with the walls of the crotch formed at the junction of the flanges of the standard 14 to hold the carriage 16 at a selected height on the standard 14.

Carried by and extending outwardly from the carriage 16 in axial alignment with the thumb screw 26 is a support 28 carrying at its end remote from the carriage 16 a pair of divergent arms 30.

These arms 30 lie along divergent axes which lie at 45° from the longitudinal axes of the support

55

28 and are provided at their ends remote from the support 28 with convergent line supporting fingers 32 which lie along axes which lie at 90° from the axes of the arms. The ends of the fingers 32 remote from the arms 30 lie parallel with the axes of the arms 30 and are grooved as at 34 to accommodate a guide line 36 which marks the line to which are laid building units employed to construct a wall W on the foundation 12. The faces 38 of the fingers 32 having the grooves 34 therein lie exactly perpendicular to one another so that when the carriage is being vertically positioned on the standard 14 portions of the faces 38 may engage a course of building units already laid in the wall W to insure accuracy in locating the guide line 36.

The outer sides of the fingers 32 and the outer ends of the arms lie in planes which lie perpendicular to the faces 38 so that when the device is employed to guide the construction of the inner side of the wall W as suggested by the dotted lines in Figure 1 the guide line 36 will be held in proper position between vertically spaced guide pins 40 which project perpendicularly from the sides of the fingers 32. Thus the faces 38 and pins 40 provide stops which serve to avoid the pinching of the guide line between the fingers 32 and a wall W.

In the modified form of the invention illustrated in Figures 4 through 6 inclusive a standard designated generally 50 is supported adjacent each corner of a building structure 10 having a foundation 12. Each such standard 50 comprises an elongated circular cylindrical column 52 carrying an outwardly extending radial fin 54 which extends throughout the entire length of the column 52 and serves as a support to which column supporting brace bars (not shown) are adapted to be detachably connected. Each column 52 is provided in its outer side diametrically opposite the fin 54 with a longitudinally extending transversely V-shaped groove 56.

Mounted for vertical movement on each column 52 is a carriage designated generally 58 comprising a ring-shaped body 60 having a longitudinal slot 62 extending therethrough for accommodating the fin 54. Formed in the body 60 diametrically opposite the slot 62 is an internally screw threaded opening 64 which aligns with the groove 56 in the column 52. A thumb screw 66 extends through and threadedly engages the threads of the opening 64 and is provided with a point 68 which enters the groove 56 to engage the walls thereof and hold the carriage 58 at a selected height on the column 52 and the carriage against rotation about the column.

Carried by and extending outwardly from the carriage 58 adjacent the lower end thereof and equi-distant from opposite sides of the axis of the opening 64 are spaced parallel arms 70 carrying at their ends remote from the carriage 58 inwardly extending return bends 72 carrying inwardly extending parallel members 74 which are connected at their ends remote from the return bends 72 by a bight portion 76. As illustrated in Figure 6 the arms 70, return bends 72, parallel members 74 and bight portion 76 are of appreciable depth and the parallel members 74 and bight portion form a yoke which extends between the arms 70 intermediate the ends thereof. Extending through the parallel members 74 between the return bends 72 and the bight portion 76 are relatively deep slots 78 which open through the upper edges of the parallel members for the reception of a guide line 80 (Fig. 4) which lies adjacent the

wall W under construction to guide the placement of building units in said wall. Carried by and extending outwardly from the return bends along axes which lie at 45° from the axis of the opening 64 are vertically spaced divergent stop pins 82 which bear against adjacent inner faces of a wall W to support the guide line 80 in proper position and avoid pinching the line. Similar vertically spaced stop pins 84 are carried by the return bends 72 which converge along axes which lie perpendicular to the axes of the stop pins 82 and these stop pins 84 are adapted to engage adjacent outer faces of the wall W as will be readily understood upon reference to Figure 4.

In use a standard 14 is mounted in a vertical position adjacent each corner of a building with its apex disposed toward an adjacent corner of the building and its side flanges in spaced parallel relation to adjacent sides of the building. With a carriage 16 mounted on each standard 14, the lines 36 are entered into the grooves 34 and knotted as shown and will lie adjacent the side of the building to define the line to which the building units are to be laid. As the courses of building units are placed in position in the wall, the carriages 16 are moved upwardly on the standards and held in proper position thereon to lay the next course. Because the faces 38 of the fingers 32 lie exactly at 90° to one another it is obvious that when the line holder is used to define the outer perimeter of the building the faces 38 by engaging adjacent sides of a building unit will serve as gauges for establishing the proper location of the standards with relation to the wall. When employing the device to define the inner perimeter of a building structure, the standards 14 and the carriages 16 are placed as illustrated in dotted lines in Figure 1 and the lines are bent around the outer ends of the fingers 32 as shown in dotted lines in Figure 2 to lie between the guide pins 40 which like the faces 38 form stops for engaging the inner faces of previously laid courses of building units and locating the carriages 16.

In employing the modified form of the invention of Figures 4 through 6 inclusive, the standards 50 are supported vertically in spaced relation to the corners of the building with the fin 54 serving as a means to which supporting braces are attached. The carriages 58 are adjusted to selected positions on the standards and held in place by engaging the points 68 of the thumb screws 66 with the walls of the groove 56. This not only holds the carriages 58 in selected positions of elevation but also locates the carriages in exact radial position on their respective standards. With a carriage 58 thus properly supported on its respective standard a line or cord 80 is looped about the bight portion 76 and opposite ends of the looped line are passed through the slots 78 and around the return bends 72 between the stop pins 84 which when the device is used to define the outer perimeter of the building engage the outer surfaces of adjacent walls of the building to aid in locating the line guide. When the device is used to define the inner perimeter of the building the line 80 is continued around the return bends 72 and extended between the stop pins 82 which are adapted to engage the inner adjacent face of the wall to aid in locating the guide line holder.

While in the foregoing there has been shown and described the preferred embodiment of this invention it is to be understood that minor changes in the details of construction, combina-

tion and arrangement of parts may be resorted to without departing from the spirit and scope of the invention as claimed.

What is claimed is:

1. In a line or cord holder a standard adapted to be supported in a vertical position adjacent a corner of a building, a carriage mounted on said standard to move vertically thereon, means carried by the carriage for engaging the standard and holding said carriage at a selected height on said standard, spaced parallel elongated arms carried by the sleeve, a yoke carried by the arms adjacent the ends thereof remote from the sleeve, said yoke extending between the arms toward the sleeve and having guide line receiving slots extending therethrough intermediate the ends thereof.

2. In a line or cord holder a standard adapted to be supported in a vertical position adjacent a corner of a building, a carriage mounted on said standard to move vertically thereon, means carried by the carriage for engaging the standard and holding said carriage at a selected height on said standard, spaced parallel elongated arms carried by the sleeve, a yoke carried by the arms adjacent the ends thereof remote from the sleeve, said yoke extending between the arms toward the sleeve and having guide line receiving slots extending therethrough intermediate the ends thereof, and vertically spaced outwardly extending stops carried by the arms adjacent their junctions with the yoke between which extends a guide line entered into the slots in the yoke.

3. In a line or cord holder a standard adapted to be supported in a vertical position adjacent a corner of a building, a carriage mounted on said standard to move vertically thereon, means carried by the carriage for engaging the standard and holding said carriage at a selected height on said standard, spaced parallel elongated arms carried by the sleeve, a yoke carried by the arms

adjacent the ends thereof remote from the sleeve, said yoke extending between the arms toward the sleeve and having guide line receiving slots extending therethrough intermediate the ends thereof, vertically spaced convergent stops carried by the arms and forming grooves and extending inwardly therefrom along convergent axes which lie at forty-five degrees from the arms and between which is received a guide line lying in the grooves.

5 4. In a line or cord holder a standard adapted to be supported in a vertical position adjacent a corner of a building, a carriage mounted on said standard to move vertically thereon, means carried by the carriage for engaging the standard and holding said carriage at a selected height on said standard, spaced parallel elongated arms carried by the sleeve, a yoke carried by the arms adjacent the ends thereof remote from the sleeve, said yoke extending between the arms toward the sleeve and having guide line receiving slots extending therethrough intermediate the ends thereof, vertically spaced convergent stops carried by the arms and forming grooves and extending inwardly therefrom along convergent axes which lie at forty-five degrees from the arms and between which is received a guide line lying in the grooves, and vertically spaced divergent stops carried by the arms and extending outwardly along divergent axes which lie perpendicular to the axes of the convergent stops and between which a guide line lying in the slots is received after passing between the convergent stops.
